DESIGN FOR LACE

Hans Albert Philips, Stratford, Conn, assignor to The American Fabrics Company, Bridgeport, Conn., a corporation of Connecticut

Application June 30, 1938, Serial No. 78,165

Term of patent 14 years

To all whom it may concern:

Be it known that I, Hans Albert Philips, a citizen of the United States, residing at Stratford, county of Fairfield, and State of Connecticut, have invented a new, original, and ornamental Design for Lace, of which the following is a specification, reference being had to the accompanying drawing, forming part thereof.

The figure is a plan view of a piece of lace, showing my new design.

I claim:

The ornamental design for lace, substantially as shown.

HANS ALBERT PHILIPS.
